(57) **CLAIM**

The ornamental design for an interchangeable vehicle antenna, as shown and described.

DESCRIPTION

FIG. 1 is a perspective view of an interchangeable antenna, showing a first embodiment of our new design;

FIG. 2 is an exploded front elevational view of FIG. 1, the rear elevational view being a mirror image thereof;

FIG. 3 is an exploded right-side elevational view of FIG. 1, the left-side elevational view being a mirror image thereof;

FIG. 4 is an exploded top plan view of FIG. 1;

FIG. 5 is an exploded bottom plan view of FIG. 1;

FIG. 6 is a cross-sectional view, taken along line 6--6 of FIG. 2;

FIG. 7 is a perspective view of a second embodiment thereof;

FIG. 8 is an exploded front elevational view of FIG. 6, the rear elevational view being a mirror image thereof;

FIG. 9 is an exploded right-side elevational view of FIG. 6, the left-side elevational view being a mirror image thereof;

FIG. 10 is an exploded top plan view of FIG. 6;

FIG. 11 is an exploded bottom plan view of FIG. 6; and,
FIG. 12 is a cross-sectional view, taken along line 12--12 of FIG. 8.

The broken lines showing a vehicle in FIGS. 1 and 6 depict environmental matter and form no part of the claimed design. The remaining broken lines depict portions of the interchangeable vehicle antenna that form no part of the claimed design.
